BALL PISTON PUMP

Johannes Joseph Günther, Hamburg-Harburg, Germany, assignor to himself and Malte Wilhelm Rönnbom and Olga Maria Carolina Rönnbom, both of Lingarden, Ystad, Sweden

Application January 8, 1952, Serial No. 265,477

3 Claims. (Cl. 103—117)

1

In the known ball pumps of the recent art, the driving shaft as well as the loose shaft are each securely coupled to a double action piston, wherein the pistons are turned over at 90° to each other. These ball pumps have only four piston chambers. The ball itself is turned, by rotation of the driving shaft, by the piston of the driving shaft acting as a driver, and is directed in such a manner by the piston of the loose shaft that the ball carries out an oscillatory movement, whereby the piston chambers alternately open and close. The pumping process is thereby carried out. The ball itself is not coupled fast to one of the two shafts but lies loosely in the housing and is controlled by the piston inside the ball cup of the housing. The ball of this pump will therefore be referred to as a ball piston, because it carries out the pumping process whilst the piston itself only carries out a rotary movement on its shaft.

The ball pumps made in practice and which are also made reversible, serve for the feeding of viscous liquids. All efforts to use the ball pumps also for fluid drives have hitherto been unsuccessful. With the present trials with ball pumps of the previous constructions there were established as definite failings:

1. With low driving force, the ball is forced against the housing by the liquid pressure, whereby considerable friction losses are entailed which, with higher pressures, such as are necessary for fluid drives, will so seriously lower the working efficiency of the pump, that its application for fluid drives would no longer be economical.

2. Through the high friction of the ball with the housing the pump, and thereby the driving fluid, will be warmed more than is permissible.

3. With higher speeds of rotation, as are usual with the motors in use, the above-named failings are further increased by the greater centrifugal force because this forces the freely-movable ball harder against the housing and increases the power-consuming friction.

4. Because of the low number of the pistons of the known ball pump in the dead-point position only one piston chamber is in operation on the suction side and one on the pressure side, whereby the rotation moment as well as the fluid stream will be too disproportionate. It has been found that the above-named failings are inherent in the construction of the ball pump, and, in the condition of their technical development hitherto, could not be overcome.

The advance in the practice which has been in question for 30 years i. e. fixed positioning of

2

the ball on a through-going driving shaft and elimination of the loose shaft is now fulfilled by the present invention.

The present invention discloses a basically altered construction of the ball pump and contains all its features. By this means a decisive advance in the development and application of the ball pump is achieved.

The essential advantages arising therefrom are:

(a) Now only one strong driving shaft passing through the ball is coupled fast to the ball and carried in bearings at both side of the housing. By this means, and through the arrangement of special controlling members for the piston, the loose shaft can be eliminated. The fluid pressure will hereinafter act from the ball directly on the driving shaft and from this latter on the shaft bearings at both sides. The unfavourable oscillating movement of the ball in the ball pump of known construction is now avoided so that this latter, in the present invention, only carries out simple rotary motion.

(b) The prejudicial effect of the centrifugal force is borne by the through-going driving shaft, because the ball can no longer be pressed against the housing and thus no friction can occur between the ball and housing.

Also, the swinging forces operating on the five pump pistons will be removed by suitable provisions so that, here also, no friction on the housing can take place. An unallowable heating of the driving fluid will thereby be avoided.

(c) In the present embodiment a number of pistons of simple operation can be arranged in a circle, whereby the rotational moment as well as the fluid stream of the pump will be increasingly proportional.

(d) The pumping process is carried out by the half of the ball lying opposite to the driving side, whilst at the other side are disposed the controlling means. By this means, an especially compact construction of the pump is made possible.

(e) The controlling part permits a control of the driving quantities and an alteration of direction of the fluid stream with direction of rotation and speed of rotation of the motor remaining the same.

The higher working efficiency of the pump according to the present invention to be expected from the above-named proposals will permit its application as primary and secondary parts of a transmission.

The pump is illustrated by way of an example as a primary driver in the drawing, wherein:

Fig. 1 shows a vertical section of the machine along the line A—B of Fig. 2 with placing of the control at highest power.

Fig. 2 is a horizontal section of Fig. 1 along the line C—D or C¹—D¹ in Fig. 3, with positioning of the controlling member at no-load running.

Fig. 3 is a view of the ball, (part 1) and arcuate piston (parts 2 to 6) and driving shaft (part 7), from "D" or "B."

Fig. 4 is a partial section of Fig. 2 along E—F.

Fig. 5 is a plan view of the coupling.

Fig. 6 is a plan view on the driver part 11a 15 and the arcuate piston 2.

The pump parts 1 to 7 and 10 to 12 remain, with all movements, at the same separation from the middle point of the ball.

The pump is driven by the through-going driving shaft 7 directly coupled with the motor, which shaft is carried in bearings 20 and 21 at both sides of the housing 14. The ball body 1 is rigidly coupled to the driving shaft 7. If the shaft 7 is set in rotary motion the part 1 and the arcuate pistons 2 to 6 are simultaneously carried therewith and in their turn the parts 11, 8, 9, 10 and 15 are set in rotary motion by the driver 11a about an axis O—P inclined at an angle α to the shaft 7. By this means the pump chambers are opened and closed one after the other, and the pumping process thus carried out.

As is shown in Figs. 1 and 3, the piston chamber at 2 is quite open and filled after the suction. With further gradual rotation of the ball 1 past the position of the arcuate pistons 5 and 6, up to rotation about 180°, the piston chamber will be completely closed and thereby emptied. With rotation of the ball back into its starting position, there is again the gradual sucking in of the liquid up to complete filling of the chamber. At each reversing and positioning of the stationary but adjustable support 12 one side of the ball becomes the pressure side and the other side the suction side. With no-load running the axis O—P corresponds with the shaft axis. The position of the axis O—P is controlled by the control member 13 through the support 12.

Part 12 is movably carried at 16 and engages at 17 in the rotary piston carrier 11 whereby the rotary movement thereof about the axis O—P is made possible.

Instead of the plain bearings 17 there can be used ball bearings. In order to prevent the rising of the parts 12 and 11 from their bearings at 16 and 17, the piston carrier 11 is movably carried at 18 on the reduced ball half 1.

In order to permit reversal, there is provided in the piston carrier 11 a bell-shaped cavity 22 and in the support 12 a slot 23, in order to allow the shaft 7 to pass unhindered through the parts 12 and 11.

Fig. 3 shows the ball 1 with 5 rectangular cavities in which the arcuate pistons 2 to 6 are disposed. The section lines of the five central planes of these cavities correspond with the shaft axis.

The movements of the pistons occur on the meridians of the ball. Nevertheless, an inaccuracy of manufacture, that is to say a small deviation of the arcuate pistons 2 to 6 from the meridian, is without prejudicial effect on the pumping process, in so far as the ball cavities each remain in a plane.

With the rotation of the ball 1 the ends of the

pistons 2 to 6 alter their distance from the axis 1. Thereby there is also altered the opposite position of these ends in the circumferential direction. As a result of this, there is simultaneously brought about, as shown in broken line in Fig. 5, a rotation of the parts 10, 11 and 15 up to the maximum angle α as far as positioning of the arcuate pistons 2 to 6 at the piston carrier 11. This movement is made possible by the linkage consisting of the cylinder 8 constructed transversely in the cylindrical part 9 and the ring 10 similarly movably engaging therein. The parts 8 and 9 can be replaced by a ball joint. The ring 10 has five cavities for the driver 11a. The parts 15 transfer the pressure removed from the piston carrier 11 onto the arcuate pistons 2 to 6 (piston pressure) whilst part 10 fixes the arcuate pistons 2 to 6 in their position to the piston carrier 11, thereby allowing the alteration of the piston position at the opposite side.

By this linkage, moreover, inaccuracies in the manufacture of the pump parts will be compensated for, so that power-absorbing binding and disproportionate requirements of the pump parts will be avoided. The drivers 11a are in movable pre-tensioned contact at 19 with the arcuate pistons 2 to 6. The separation a in Fig. 6 between the driver 11a and the arcuate piston 2 is stipulated by the opposite separation of the arcuate pistons 2 to 6 altered by the rotation of the ball, so that with rotation of the ball 1 the drivers do not all come into operation simultaneously. The driver 11a which bears at 19 with tension on the arcuate pistons 2 to 6, prevents in this way the prejudicial action of centrifugal force on the arcuate pistons 2 to 6 and the raising thereof from the ball 1 and thus also the friction of the arcuate pistons 2 to 6 on the housing walls 14. The pump works without valve means.

In application as a hydraulic motor the control parts 13 and 12 can be omitted and piston carrier 11 be carried at 17 in the housing 14 because, for example, with ships gear change and reversing gear the control of the speed and direction of rotation of the ships screw will be carried out from the crank 13 at the primary part of the driving motor.

For lathes, power vehicles and automobiles the same applies.

I claim:

1. A fluid pump comprising in combination a stationary housing having a spherical surface therein and inlet and outlet port means providing communication between the interior and exterior of the housing, bearings mounted in the housing at opposite sides thereof, a rotary driving shaft carried in said bearings and disposed diametrically through the housing, a rotary ball secured on the driving shaft and forming a close fit but not in contact with the spherical surface of the housing, said ball having a number of peripheral pumping chambers therein equally-spaced circumferentially about the axis of rotation of the ball, each pumping chamber being arcuate and having its central plane coincident with the axis of the driving shaft, each such pumping chamber opening at the periphery of the ball and being bounded thereat by the spherical surface of the housing, a stationary support within the housing, a rotary piston carrier journaled thereon with the axis of rotation of the piston carrier inclined with respect to the axis of rotation of the ball, and a number of

arcuate pistons disposed one in each pumping chamber of the ball and secured to the piston carrier such that the pistons rotate about an axis parallel to that of the piston carrier and correspondingly inclined to the axis of the ball whereby rotation of the ball and pistons therein causes the pistons to be reciprocated arcuately in the pumping chambers about an axis perpendicular to the axis of said driving shaft, the inlet port means of the housing opening at the spherical surface thereof at a position to correspond to a greater volume of each pumping chamber as the piston moves therein, and the outlet port means of the housing opening at the spherical surface thereof at a position to correspond to a lesser volume of each pumping chamber as the piston moves therein.

2. A fluid pump comprising in combination a stationary housing having a spherical surface therein and inlet and outlet port means providing communication between the interior and exterior of the housing, bearings mounted in the housing at opposite sides thereof, a rotary driving shaft carried in said bearings and disposed diametrically through the housing, a rotary ball secured on the driving shaft and forming a close fit but not in contact with the spherical surface of the housing, said ball having a number of peripheral pumping chambers therein equally-spaced circumferentially about the axis of rotation of the ball, each pumping chamber being arcuate and having its central plane coincident with the axis of the driving shaft, each such pumping chamber opening at the periphery of the ball and being bounded thereat by the spherical surface of the housing, a non-rotary but adjustable support mounted in the housing for movement within limits about an axis coincident with the centre of the ball and at right angles to the axis of the driving shaft, said support having an elongated slot receiving the driving shaft, means within the housing in engagement with said support and protruding externally from the housing for adjustment of the position of the support from the exterior, a rotary piston carrier journalled on the support with its axis of rotation at an angle to the axis of rotation of the ball according to the position of adjustment of the support, and a number of arcuate pistons disposed one in each pumping chamber of the ball and secured to the piston carrier for rotation about an axis parallel to that of the piston carrier and at a corresponding angle to the axis of rotation of the ball whereby rotation of the ball and pistons therein causes the pistons to be reciprocated arcuately in the pumping chambers about an axis perpendicular to the axis of said driving shaft, the inlet port means of the housing opening at the spherical surface thereof at a position to correspond to a greater volume of each pumping chamber as the piston moves therein, and the outlet port means of the housing opening at the spherical surface thereof at a position to correspond to a lesser volume of each pumping chamber as the piston moves therein.

3. A fluid pump comprising in combination a

stationary housing having a spherical surface therein and inlet and outlet port means providing communication between the interior and exterior of the housing, bearings mounted in the housing at opposite sides thereof, a rotary driving shaft carried in said bearings and disposed diametrically through the housing, a rotary ball secured on the driving shaft and forming a close fit but not in contact with the spherical surface of the housing, said ball having a number of pumping chambers therein equally-spaced circumferentially about the axis of rotation of the ball, each pumping chamber being arcuate and having its central plane coincident with the axis of the driving shaft, each such pumping chamber opening at the periphery of the ball and being bounded thereat by the spherical surface of the housing, a non-rotary but adjustable support mounted in the housing for movement within limits about an axis coincident with the centre of the ball and at right angles to the axis of the driving shaft, said support having an elongated slot receiving the driving shaft, means within the housing in engagement with said support and protruding externally from the housing for adjustment of the position of the support from the exterior, a rotary piston carrier journalled on the support with its axis of rotation at an angle to the axis of rotation of the ball according to the position of adjustment of the support, a ring on the support coaxial with the carrier, a number of arcuate pistons disposed one in each of the pumping chambers of the ball and slidably engaged with the ring for circumferential movement with respect to the carrier, the pistons being rotatable with the carrier about an axis at an angle to the axis of the ball whereby rotation of the ball and pistons therein causes the pistons to be reciprocated arcuately in the pumping chambers about an axis perpendicular to the axis of said driving shaft, an annular pressure plate arranged on the carrier between the carrier and the pistons to receive the thrust of the pistons during pumping, and a resilient annular flange on the carrier engaged under tension with each piston to urge the piston inwardly against the ball and prevent outward movement of the piston under centrifugal force, the inlet port means of the housing opening at the spherical surface thereof at a position to correspond to a greater volume of each chamber as the piston moves therein, and the outlet port means of the housing opening at the spherical surface thereof at a position to correspond to a lesser volume of each pumping chamber as the piston moves therein.
